UNITED STATES PATENT OFFICE.

JOHN W. KALES, OF FRANKLINVILLE, NEW YORK.

GAS OR OTHER EXPLOSIVE ENGINE.

No. 880,741.

Specification of Letters Patent.

Patented March 3, 1908.

Application filed February 13, 1906. Serial No. 300,849.

To all whom it may concern:

Be it known that I, JOHN W. KALES, a citizen of the United States, residing at Franklinville, in the county of Cattaraugus and State of New York, have invented certain new and useful Improvements in Gas or other Explosive Engines, of which the following is a specification.

The present invention relates to improvements in gas or other explosive engines, and particularly to the mechanism for admitting the exploded charge from the explosion chamber to the engine to be driven.

In many gas engines as now constructed and operated, it has been found very difficult to operate the valve, which closes the explosion chamber while charging, at the proper instant to get the greatest power from the explosion to the engine, for various reasons, one of which is that a mechanically actuated valve often fails to open to its extreme position with sufficient rapidity to pass the charge to the engine.

The objects of the improved construction shown herein are to provide, in an explosive engine, a valve which may be positively closed and so held, by an electro-magnet, and provision is made for an electric circuit including a contact surface or point on a moving element of the engine, whereby the valve may be held in closed position when the circuit is closed, and the circuit broken almost simultaneously with the explosion in the chamber thus releasing the valve and permitting the passage of the exploded charge to the engine.

In the accompanying drawings I have illustrated one example of the physical embodiment of my invention constructed according to one mode I have adopted for the practical application of the principles thereof.

The invention is shown in conjunction with a rotary or turbine engine for convenience of illustration, but it will of course be understood that the principles involved may be adapted to many forms of explosive engines.

Referring to the figures of drawing: Figure 1 is a side elevation of an explosive engine of the turbine or rotary type, showing the parts necessary to illustrate my invention, and showing also the drive shaft in section with a disk thereon carrying an electrical contact piece. Fig. 2 is a top plan view of Fig. 1. Fig. 3 is a partial elevation, similar to Fig. 1, but with parts of the mechanism in section for convenience of illustra-

tion, and Figs. 4 and 5 are detail views of a modified form of the means for timing the explosion in the explosion cylinder.

As before stated a rotary explosive engine is shown in conjunction with the improvements of the present invention, and the numeral 1 designates the main shaft or drive shaft of such engine; 2, the bearings or supports for said shaft; 3, a casing for the engine; 4, a rotary piston wheel, adapted to rotate with the shaft within the casing; 5, buckets or pockets in the periphery of the piston wheel; 6, an expansion chamber in open communication with the interior of the engine casing and with the pockets or buckets 5 of the piston wheel; 7, a hinged valve, adapted to swing, and employed for the purpose of closing one end of the explosion chamber; 8, the pivot or hinge of the valve, said pivot being hung in the upper wall of the explosion chamber; 9, a pocket or seat formed in the upper wall of the expansion chamber to receive the hinged valve when the same is opened by the force of an explosion; 10, the explosion chamber; 11, a shoulder formed in the lower wall of the explosion chamber providing a seat for the valve, when the same is closed; 12, an ignition device of any suitable construction; 13, a compressor; 14, an air inlet pipe from the compressor to the explosion chamber; 15, a check valve in the air inlet pipe; 16, a gas inlet pipe from the compressor to the explosion chamber; and 17, a check valve in said pipe; 18 and 19 are gas and air supply pipes, respectively, which may receive these elements from any suitable source of supply; 20, is an electro-magnetic coil surrounding and mounted upon the outer walls of the explosion chamber.

The compressor is driven as usual from the shaft through the pinions 21 and 22, the latter having connected thereto the rod 23, which is in turn connected with the stem 24 of the piston 25 in the compressor; 26 indicates a balance wheel of usual pattern.

Located upon the shaft 1 and rotating therewith is a disk 27 having interposed between its hub and the shaft, a non-conducting sleeve or insulator 28, and a projection or rib 29, formed concentric with the disk, provides a moving contact element adapted to frictionally engage a stationary contact arm 30, secured upon the engine casing for convenience, as the disk revolves with the shaft.

In operation the engine may be started in any usual manner, the compressor operates

to compress a charge of gas and air in the explosion chamber, and the charge is exploded as usual.

It will be understood that the valve which constitutes the armature for the magnet, and the explosion chamber are constructed of magnetic metal; and the material of which the expansion chamber is constructed, is of non-magnetic metal.

10 It will be understood that I do not limit myself to the hinged or swinging form of valve shown, nor to the precise location of the valve, it being only necessary that the valve be disposed between the explosion 15 chamber and the engine. A reciprocating engine might be used, and different kinds of valves employed, such for instance as a plug valve, adapted to fit, when closed, in a complementary-seat.

20 On reference to Figs. 4 and 5, it will be seen that the pinion 27' of the main shaft, and the gear 28' on a short shaft, will operate to energize or de-energize the magnet, say once in every three revolutions of the main 25 shaft, thus demagnetizing the valve so that an explosion may occur once in three revolutions of the shaft of the engine; or the gear 28' may be used instead of the gear 22, and thus the moving contact disk or rib be located 30 on the pinion for driving the compressor. This construction will produce an explosion at the end of every charging stroke of the compressor.

Larger or smaller gears may be substituted 35 for the gears 27' and 28', contact piece 29' being employed on each of the lower pinions, and the stationary contact piece 30' may be moved at will to positions required by the size of the pinion used on the lower shaft. 40 Thus the timing of the explosion may be varied to suit the requirements of the case, and the valve be held in closed position until the pressure in the explosion chamber reaches any desired capacity within limits.

45 The dimensions of the arc on the rotating member, constituting the moving contact piece may be varied to suit the circumstances of the case.

From the drawings and description it is 50 evident that this invention involves many advantages applicable to this class of engines. One of the great advantages is that the valve may be held in closed position, by the magnetic energy, until the charge in the explosion chamber reaches its predetermined maximum pressure preparatory to the explosion thereof, and the valve, or armature of the magnet, be de-magnetized at varying intervals, but with accuracy and reliability.

55 Many other modifications, changes, and alterations may be made in the practical application of the principles of the invention, within the scope of my claims, without de-

parting from the spirit thereof, as the drawings illustrate only several examples of the 65 physical embodiment of the invention, and I contemplate changes and alterations in the practical use of the invention.

Having thus described my invention, what I claim and desire to secure by Letters Patent is:

1. In an engine the combination, of an explosion chamber, a hinged valve located between said chamber and the engine piston, a coil surrounding the walls of said chamber 75 and said walls forming the core of a magnet, and electrical connections to said coil whereby the valve is held in closed position.

2. In an engine the combination with an explosion chamber, of a valve located between said chamber and the engine piston, a coil surrounding the walls of the explosion chamber and said walls forming the core of a magnet whereby when the magnet is energized the valve is held closed; a stationary 85 contact point, and a moving contact point on the engine, in electrical circuit, for releasing said valve.

3. The combination with an explosion chamber having a shoulder formed at its end, 90 of a swinging valve adapted to bear against said shoulder and close the chamber, and an electro-magnetic coil surrounding the walls of said chamber adapted when energized to hold the valve closed, and said walls forming the 95 core of a magnet; and means for de-energizing the magnet to permit the valve to be opened at the time of explosion.

4. The combination in an explosive engine, 100 of an expansion chamber and an explosion chamber and a hinged valve located therebetween, a coil surrounding the walls of the explosion chamber and said walls forming the core of a magnet, and electrical connections for energizing the magnet to hold the valve 105 closed and de-energizing the magnet to permit the valve to open.

5. In an engine the combination of an explosion chamber and an expansion chamber 110 and a valve hinged therebetween, a valve seat formed at one end of the explosion chamber, a coil surrounding the walls of the explosion chamber and adapted when energized to hold the valve against its seat, the walls of the explosion chamber forming the 115 core of a magnet, and an electrical circuit including said coil having means therein for intermittently magnetizing and demagnetizing the valve to close and open the same.

In testimony whereof I affix my signature 120 in presence of two witnesses.

JOHN W. KALES.
